VEHICLE DOOR LATCH MECHANISM

Waldemar A. Endter, Long Beach, Calif.

Application March 15, 1949, Serial No. 81,547

9 Claims. (Cl. 292—341.13)

This invention has to do with latch devices, typically latch mechanisms for automotive or other vehicle doors and closures, and is directed particularly to improvements in a type of floating (i. e., swinging and bodily movable) bolt latch device of the general character dealt with in my copending application Serial Number 783,184, filed October 30, 1947, on Floating Bolt Latch Mechanisms, now Patent No. 2,569,046.

Briefly, the bolt structure and mode of operation with which I am herein concerned, involves a housing applicable, for example, to an automobile door pillar, and containing a bolt projecting from the housing for engagement with a door-carried keeper. The bolt may be rotatable in response to both manual effort and spring urging. The desirable characteristics and advantages of a take-up action (tending constantly to crowd the door tightly closed against the pillar) is accomplished by the capacity of the bolt for rotation and its bodily displacement within the housing by a movable, and preferably rotatable, spring urged cam interposed between the bolt and housing. These features are embodied generally in the disclosure of my earlier filed application referred to above.

The present invention has for its primary object to improve the bolt, cam and housing assembly in various respects favoring the practicability and cost of manufacture, as well as the important requirement of initial and sustained accuracy in the shape and dimensional relation of the parts.

Specifically, the invention aims to insure accuracy in the support given the cam at spaced locations against the housing, by engaging the cam periphery at both locations directly against the side wall of the housing so that the cam occupies the full dimension of the housing chamber between those locations. The accuracy with which the housing may be formed in production, assures maintenance at all times of the exact desired spacing and shaping of the cam contacted housing surfaces.

Also contemplated are novel features with respect to the manner in which the cam and bolt actuating springs are accommodated within the housing; while the cam is permitted to extend therein from wall to wall. Further, the invention provides the cam with novel flanged form and shape characteristics contributing to desirable bearing surfaces as well as the accommodation of the springs within the cam.

All the aforementioned features, as well as additional objects and details will be understood

to better advantage from the following description of an illustrative embodiment shown by the accompanying drawing, in which:

Fig. 1 is a view showing the bolt and its housing in outside elevation, engaged in latched condition with the keeper parts;

Fig. 2 is an enlarged view of the bolt and housing in the aspect of Fig. 1;

Fig. 3 is a sectional view on line 3—3 of Fig. 2;

Fig. 4 is a view similar to Fig. 2 with a portion of the housing broken away to directly expose the bolt and cam, the bolt here appearing in retracted position;

Fig. 5 is a view taken on line 5—5 of Fig. 3, showing the parts as viewed from the inner side of the housing;

Figs. 6 and 7 are perspective views, respectively of the bolt and cam;

Fig. 8 is a view similar to Fig. 5 showing a variational form of the invention; and

Fig. 9 is a fragmentary section taken on line 9—9 of Fig. 8;

The bolt and cam assembly is contained within a housing, generally indicated at 10, comprising a base plate 11 provided with holes 12 for reception of screws 13, see Fig. 3, for attachment of the housing to the usual automobile door pillar indicated by the dot-dash lines 14. Formed integrally with the base plate is a shell 15 containing and defining the bolt and cam chamber 16, the outer and lower walls 17 and 18 of the shell being cut away to form the bolt-passing opening 19. As illustrated, except for the opening, the walls of the shell are continuous, thus affording a compact and deformation-resistant structure giving bearing support to the cam, as later explained.

Chamber 16 contains the cam 20, see particularly Fig. 7, which has an outer curved flange 21, a portion 22 of which is struck inwardly to form the spring-receiving notch 23, and an inner segmental circular flange 24 of somewhat greater than 180 degree extent. Flanges 21 and 24 are connected by the radial web 25 which in the position of the cam assumed within the housing, is adjacent the outer wall 17 thereof, as shown in Fig. 3.

The bolt 26, see Fig. 6, has a segmental cylindrical hub 27 seated concentrically within opening 28 defined by the cam flange 24, so that the bolt is carried by the cam and rotatable relative thereto about the center of axis at 29 (see Fig. 4) of opening 28. The bolt has an outer curved keeper engaging face 30, beyond which the bolt is recessed at 31 for engagement with

the keeper in the safety catch position. Rotation of the bolt in an antilatching direction is arrested by engagement of the bolt surface 32 with the housing shoulder at 33. Opposite swinging movement of the bolt is limited by the engageability of its surface 34 with the housing shoulder 35.

The cam is constantly urged in a direction tending to bodily thrust or displace the bolt in a latching direction and relative to the housing 10, by coil spring 36, one end 36a of which is received within the cam notch 23 and bears against the cam portion 22, the opposite end 36b of the spring being stationarily anchored within an opening in the housing. As will be understood, the tendency of spring 36 is to urge the cam for rotation in a counterclockwise direction as viewed in Figs. 1, 2 and 4, and in so doing to bodily thrust the bolt outwardly from the housing by reason of the later described eccentricity of the cam relative to the housing.

The bolt 26 is rotatable relative to the cam, against the resistance of a coil spring 38 received concentrically within spring 36 about an extension 39 of the bolt hub. One end 38a of the spring is received within slot 40 in the hub extension, and outer end 38b of the spring is stationarily received within an opening in the housing. Spring 38 tends to rotate the bolt counterclockwise relative to the cam and to a limiting position (with respect to the cam) at which the bolt shoulder 41a is engageable against the end face 41 of the cam flange.

As best illustrated in Fig. 4, the cam has a curved surface 42 engageable against the housing surface 43 which may have substantially corresponding curvature. The opposite side of the cam flange has a surface 44 curved at a relatively larger radius continuing along increasing curvature at 45 to the flattened surface 46. In all positions, the cam is engageable against the curved housing surfaces 43 and 47, and in the fully retracted position of the bolt shown in Fig. 4, the cam may engage or approach engagement with the housing surface 49. Referring to Fig. 2, it will be observed that the arcuate extent of the housing surface 47 is such that the cam is confined between that surface and the housing surfaces 43 and 50 against bodily displacement in the line of the thrust exerted against the bolt, so that the cam becomes releasably wedged against displacement in all latched positions of the bolt wherein the bolt thrust is transmitted to the cam.

It will be understood that the described bolt and cam assembly may be used in conjunction with any desired form of keeper. Merely as illustrative, I have shown a keeper 51 pivotally mounted for swinging movement about a door-carried pin 52 into and out of overlapping relation with the bolt 26, all as more particularly dealt with in my copending application Ser. No. 705,843, filed October 26, 1946, now Patent No. 2,569,045. For present purposes, it will suffice to explain that in latched condition of the parts, the keeper assumes the position shown in Fig. 1, in which its top surface 53 is engaged by the curved face 30 of the bolt which, under the influence of the cam 20 exerts a constant take-up thrust against the keeper. In the safety catch position of the parts, the keeper nose 54 is receivable within the bolt recess 31. A dove-tail relation is formed by the illustrated engagement of the bolt against the keeper, and the engagement of the top surface of the housing shell

with a stationary door-carried lug or abutment 55.

In considering the operation of the mechanism, assume that the door-carried keeper parts 51 and 55 are brought into latched association with the bolt and housing, by movement of the keeper parts from the right, ultimately into the fully latched condition illustrated in Fig. 1. In the open position of the door, the bolt 26 assumes the fully thrust-out position shown in Fig. 2 resulting from counter-clockwise rotation of the cam to the limiting position established by its engagement against the bolt shoulder 40 and engagement of the bolt face 34 against the housing shoulder 35. Upon engagement with the keeper, the bolt is rotated clockwise, carrying with it the cam against the resistance of spring 36. When released for rotation beyond the safety catch position, in which the keeper nose 54 is receivable within the bolt recess 31, the bolt is snapped by its spring into the keeper, independently of the cam. Then the cam action follows and advances the bolt along the keeper surface 53 to the fully latched position of Fig. 1, and at the same time to thrust the bolt outwardly of the housing to effect the take-up action tending to crowd the door against the usual pillar cushion (not shown). As previously indicated, the bolt thrust is taken by engagement of the cam against the housing surface 47 and 50, the relative angularities of which are sufficient to wedge the cam against retraction from any advanced position, while at the same time leaving the cam sufficiently free for further advancement under the influence of spring 36, as the bolt is brought to full home position. As explained in my copending application referred to above, the parts may be disengaged from latched association by swinging the keeper 51 about pivot 52 downwardly away from the bolt.

Figs. 8 and 9 illustrate a variational form of the invention in which the bolt thrust is transmitted and at one side of the cam to the housing wall, and at the other side of the cam to a pin support so positioned and shaped as to hold the cam against retrograde movement, while permitting its advancement under the influence of the cam-urging spring. Here the curved portion 56 of the outer cam flange is shown to be engageable against the correspondingly curved housing surface 56a and the straight surface 57 beyond. The opposite curved side 58 of the cam flange is engageable against the curved housing surface 59 and also against a cylindrical surface pin 60, see Fig. 9, terminating in the outer housing wall 61 and in the inside cover plate 62. As will be apparent, in all latched positions of the bolt, its line of thrust transmission to the cam is between the housing surfaces 56, 57 and pin 60, and accordingly the cam is given such wedge engagement with the housing and pin surfaces as will prevent antilatching cam rotation, while permitting advancement of the cam as the bolt progressively is moved to full home position.

The primary purpose of engaging the cam against the pin 60, is to further assure unintentional retraction of the cam when the bolt is in latch position. Preferably the element 60 consists of a hardened steel pin presenting against the cam a convex surface which may tend to penetrate very slightly into the cam surface, particularly if the latter is a softer metal, and thus assure proper retention of the cam in all of its bolt latching positions.

I claim:

1. In a latch mechanism for a stationary member and a swinging closure member, the combination comprising: a housing adapted to be mounted on one of the members and including a base and a wall projecting outwardly from said base and defining the interior sides of a bolt chamber, portions of said sides being concavely curved; cam means mounted for rotation within said chamber and including a radial web having an outer axially-projecting flange provided with convex peripheral surface portions engaging said curved portions of said chamber sides at peripherally spaced locations; and a bolt carried by said cam means for limited rotation with respect thereto and having a peripheral surface portion projecting out of said chamber for rotative latching engagement with a keeper mounted on the other of the members, said cam means being effective upon rotation in the direction of latching engagement of said bolt to shift the rotational axis of the latter to bodily displace said bolt, relative to the one member, in keeper-engaging direction.

2. The structure defined in claim 1 including a spring within the housing urging the cam means to rotate in a latching direction.

3. The structure defined in claim 1 including spring means contained within the confines of the cam means and separately urging the cam means and the bolt to rotate in a latching direction.

4. The structure defined in claim 1 including a pair of coil springs contained one within the other and within the housing to one side of the web, said springs engaging said cam means and the bolt, respectively, and separately urging said cam means and said bolt to rotate in a latching direction.

5. The structure defined in claim 1 in which the cam means includes an inner arcuate flange projecting axially from the web and extending through an arc greater than 180° to define a bolt-carrying recess and the bolt has a convex arcuate surface portion peripherally spaced from the keeper-engaging surface portion and fitting within said recess.

6. In a latch mechanism for a stationary member and a swinging closure member, the combination comprising: a housing adapted to be mounted on one of the members and including a base and a wall projecting outwardly from said base and defining the interior sides of a bolt chamber, portions of said sides being concavely curved; cam means mounted for rotation within said chamber and including a radial web having an outer axially-projecting flange provided with convex peripheral surface portions engaging said curved portions of said chamber sides at peripherally spaced locations and an inner axially-projecting arcuate flange extending through an arc greater than 180° to define a bolt-carrying recess; and a bolt carried within said recess for limited rotation with respect to said cam means and having a peripheral surface portion projecting out of said recess and out of said chamber for rotative latching engagement with a keeper mounted on the other of the members, said cam means being effective upon rotation in the direction of latching engagement of said bolt to shift

the rotational axis of the latter to bodily displace said bolt, relative to the one member, in keeper-engaging direction.

7. In a latch mechanism for a stationary member and a swinging closure member, the combination comprising: cam means adapted to be mounted for rotation on one of the members and having outer convex peripheral surface portions; a bolt carried by said cam means for limited rotation thereon and having a peripheral surface portion for rotative latching engagement with a keeper mounted on the other of the members; and means adapted to be fixedly mounted on the one member and defining an abutment surface having concave portions extending about said cam means in opposition to the peripheral surface portions thereof and for rotation of said cam means thereagainst, said fixed means also defining a convex abutment surface of smaller radius of curvature than and rotatively engaged by a convex peripheral surface portion of said cam means and being disposed to receive the reaction thrust of said bolt in all rotative positions of the latter, said cam means being effective upon rotation in the direction of latching rotation of said bolt to shift the rotational axis of the latter to bodily displace said bolt, relative to the one member, in keeper-engaging direction.

8. The structure defined in claim 7 in which the convex abutment surface is formed by a hardened steel pin.

9. In a latch mechanism for a stationary member and a swinging closure member, the combination comprising: a housing adapted to be mounted on one of the members and including a base and a wall projecting outwardly from said base and defining the interior sides of a bolt chamber, portions of said sides being concavely curved; cam means mounted for rotation within said chamber and having convex peripheral surface portions engaging said curved portions of said chamber sides at peripherally spaced locations; a bolt carried by said cam means for limited rotation with respect thereto and having a peripheral surface portion projecting out of said chamber for rotative latching engagement with a keeper mounted on the other of the members, said cam means being effective upon rotation in the direction of latching engagement of said bolt to shift the rotational axis of the latter to bodily displace said bolt, relative to the one member, in keeper-engaging direction; and a circular pin projecting from said base within said chamber and rotatively engaged by a convex peripheral surface portion of said cam means, said pin being disposed to receive the reaction thrust of said bolt in all rotative positions of the latter.
